UNITED STATES PATENT OFFICE.

SOLOMON PENTICO, OF WOODWARD, IOWA.

COMBINED SCOOP-BOARD AND END-GATE.

1,254,932.

Specification of Letters Patent. Patented Jan. 29, 1918.

Application filed March 13, 1917. Serial No. 154,613.

To all whom it may concern:

Be it known that I, SOLOMON PENTICO, a citizen of the United States, and resident of Woodward, in the county of Dallas and State of Iowa, have invented a certain new and useful Combined Scoop-Board and End-Gate, of which the following is a specification.

The object of my invention is to provide a combined scoop board and end gate of simple, durable and inexpensive construction.

A further object is to provide a scoop board and end gate with means for pivotally connecting the lower end of said device with a wagon bed for permitting the upper end of the end gate and scoop board to tilt rearwardly, which means comprises two hinges capable of being separated for permitting the rearward end of the scoop board and end gate to be swung outwardly, which hinge is also adjustable for making a tight joint when the device is used as an end gate and for permitting the device to be swung outwardly at its upper end and still maintain a tight joint.

A further object is to provide such a scoop board and end gate in combination with a wagon bed having a suitable protecting plate for protecting the wagon bed against the shovel or the like.

A further object is to provide simple means for securing the upper portion of the scoop board and end gate to the wagon bed in such a way as to permit the device to be locked fast to the wagon bed when used as an end gate, or to properly support the upper end of the device when the lower end is swung outwardly for permitting the grain or the like to flow out of the wagon bed.

A further object is to provide adjustable means for securing the scoop board to the wagon bed at different heights on the scoop board and end gate.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a rear elevation of my combined scoop board and end gate installed on a wagon.

Fig. 2 shows a vertical, sectional view taken on the line 2—2 of Fig. 1.

Fig. 3 shows an enlarged, vertical, sectional view, taken on the line 3—3 of Fig. 1, the scoop board and end gate being shown in its position when used as a scoop board.

Fig. 4 shows a similar view, the scoop board and end gate being shown in a different position.

Fig. 5 shows a side elevation of the rear part of the wagon bed with my improved scoop board and end gate mounted thereon.

Fig. 6 shows a rear elevation of one of the lower corners of the scoop board and end gate.

Fig. 7 shows a vertical, sectional view taken on the line 7—7 of Fig. 1, the end gate being shown in closed position, and

Fig. 8 shows a horizontal, sectional view taken on the line 8—8 of Fig. 2.

In the accompanying drawings which illustrate my invention, I have shown a portion of a wagon bed having the bottom 10 and the sides 11. Beneath the rear end of the bottom is a transverse cleat 12. Above the side 11 are side boards 13. I have shown on the inner surfaces of the walls 11 and side boards 13 at the rear ends thereof, the ordinary spaced cleats 14.

Extending across the rear end of the wagon bed bottom is an angle iron reinforcing member 17 having an upright flange placed against the rear edges of the bottom 10 and the cleat 12, and having a horizontal flange extending forwardly and countersunk in the bottom 10. The upper horizontal flange of the angle iron 17 forms a sort of plate to protect the wagon bed from a shovel pushed against the bottom of the bed from the scoop board.

Secured to the central portion of the upright flange of the angle iron 17 is a short angle iron 18 having an upright flange secured to the upright flange of the angle iron 17 and terminating short of the upper portion of the angle iron 17 and having a rearwardly extending horizontal flange, as clearly shown in Fig. 7, adapted to serve as a support for the scoop board and end gate in such a way that a portion of the angle iron 17 forms a shoulder against which the lower forward surface of the scoop board and end gate abuts.

My improved end gate and scoop board comprises an end gate which in the illustration shown is made up of a plurality of

upright members connected by transverse members 16 extending across the rear surfaces of the members 15.

The scoop board and end gate is designed to fit against the rear edges of the sides 11, as shown in Fig. 8, with its lower forward surface abutting against the upper portion of the upright flange of the angle iron 17 and with the central portion of its lower edge resting upon the horizontal flange of the angle iron 18, as shown in Fig. 7.

The scoop board and end gate is provided with side wings 19 which, when the scoop board is in its upright position, rest adjacent to the outer surfaces of the rear ends of the sides 11 and side boards 13, as shown in Fig. 8. Angle irons 20 are arranged in each case with one flange secured to the members 16 and with one flange secured to the side wing 19, as shown in Fig. 8.

I provide a hinge especially adapted for use with my scoop board, comprising a hinge member 21 extended through suitable openings in the upright flange of the angle iron 17 and in the cleat 12, as illustrated in Fig. 4, the hinge member 21 being slidable longitudinally of the wagon and having at its forward end a down-turned flange 22 for limiting the rearward movement of the hinge. Pivoted to the hinge member 22 is a hinge member 23 provided with a slot 24 to receive a keeper 25 having substantially the form of a ring or eye secured to the rear lower surface of the scoop board and end gate.

Secured on each hinge member 23 is a bracket or the like 26 having a portion 27 forming a bearing for a locking bolt 28, as shown, for instance, in Figs. 2 and 3. The bearing 27 is provided with an elongated slot 29 having at one end a downward extension 30 shown in Fig. 6. The locking bolt 28 is slidably mounted in the bearing 27 and is provided with an outwardly extending handle 31, the lengthwise sliding movement of which is limited by the ends of the slot 29.

On the locking bolt 28 is a spring 32 for yieldingly holding the locking bolt at one end of its sliding movement.

The hinges and locking bolt mechanism just described are so constructed and arranged that when the scoop board and end gate is in its upright position the hinge member 23 may be in upright position with the keeper 25 extended through the slot 24 and with the locking bolt 28 received and held by the keeper 25.

Suitably mounted on the inner surface of each side board 13 is a metal plate 33 extending rearwardly from the wagon bed and having at its rear end an upward extension 34 and having near its rear end a hole 35. The scoop board and end gate is provided with

slots or openings 36 for receiving the plates 33, the slots 36 being of such length that when the scoop board and end gate is in its position for use as an end gate resting upon the angle iron 18, the upper portions of the slots 36 will be adjacent to the upper edges of the plates 33, but slightly spaced therefrom. The slots 36 are long enough from top to bottom to allow considerable up and down play of the end gate on the plates 33.

Mounted on the end gate, on the rear surface thereof near each slot 36, is a locking device such as that already described, having similar bracket members, keepers, locking bolts and so on, the parts being so arranged that when the scoop board and end gate is in position for use as an end gate the upper locking bolts 28 may be received in the holes 35 for locking the scoop board against the rear edges of the sides 11 and side boards 13, as shown in Fig. 1.

Secured to each side wing 19 near the lower portion thereof is a chain 37, and secured to each side wing near its central portion from top to bottom is another chain 38.

Secured to the outer surfaces of the sides 11 are hook devices of substantially the form shown in Fig. 8, comprising in each case a brace member 39 having two hook members 40 and 41 spaced from each other 95 fore and aft in the wagon.

In the practical use of my improved scoop board and end gate the parts are assembled on a wagon bed as hereinbefore described. When the device is used as an end gate the end gate portion fits against the rear edges of the sides and side boards, as hereinbefore mentioned, with the upper locking bolts 28 received in the holes 35 and with the lower locking bolts 28 received in the keepers 25. In such position of the parts it will be noted that the downwardly extending flange 22 fits against the forward edge of the cleat 12, and the end gate is snugly held against the wagon. The side wings 19 receive between them the sides of the wagon bed.

The chains 37 and 38 may be drawn tight and hooked over either of the hook members 40 and 41 for affording further end gate holding means.

If it is desired to tilt the upper end of the end gate rearwardly for using it as a scoop board, the lower chains are loosened and the upper chains are changed and caused to engage the proper hook member 40 for holding the end gate in its inclined position for use as a scoop board, as shown by full lines in Fig. 3 and by dotted lines in Fig. 5.

It will be noted that the arrangement of the hinge is such that the hinge member 21 will slide forwardly during the rearward movement of the upper portion of the end gate to its position shown in Fig. 3, thereby permitting the lower inner edge of the

end gate to fit snugly against the angle iron 17 for preventing the loss of grain between the lower edge of the end gate and the rear edge of the bottom 10.

5 The upper flange of the angle iron 17 receives the impact of the shovel when the shovel is pushed downwardly and forwardly along the scoop board, and saves the rear upper surface of the bottom 10 from being 10 torn or broken by the shovel.

It will be noted that the length of the hinge member 21 is such that it is allowed a sliding movement equal in length to the thickness of the end gate 15.

15 If it is desired to move the end gate from its position shown in Fig. 2 where it is used as an end gate, for tilting its lower end outwardly and rearwardly for discharging grain at a dump or the like, the chains are

20 loosened sufficiently to permit the movement of the end gate contemplated, the locking bolts 28 are moved to release them from the holes 35, and the lower locking bolts are moved to release them from the keepers 25.

25 The handles 31 may be dropped downwardly into the extensions 32 for holding the locking bolts in their inoperative positions against the pressure of the springs 29. The hinge member 23 may then be released and the

30 bottom of the end gate can be swung outwardly to the position shown in Fig. 4 for releasing the grain in the wagon bed. The chains limit the outward movement of the end gate, the plates 33 prevent the end gate

35 from dropping downwardly, and the upward extensions 34 on said plates prevent any accidental removal of the end gate from the plates 33.

Some changes may be made in the construction and arrangement of the various parts of my improved scoop board and end gate, and it is my intention to cover by the patent to be issued upon this application any modified forms of structure or use of 45 mechanical equivalents which may come within the reasonable scope of my claims.

In the claims I have used the word "sides" to include both the side members 11 and the side boards 13.

50 I claim as my invention:

1. In a device of the class described, the combination of a wagon bed, an end gate member, means for connecting the lower edge of said end gate member to the lower part

of the wagon bed and to hold the lower ends 55 of the end gate member in different positions relative to the lower part of the wagon bed, plates secured to the side of the wagon bed and extending rearwardly therefrom, having upward extensions at their rear ends, 60 said end gate being provided with slots of greater length from top to bottom than the width of said plates, said plates and end gate having coacting means for locking the upper portion of the end gate to the wagon 65 bed, said plates being designed to support the end gate and allow certain pivotal movement thereof when the lower end of the end gate is swung rearwardly from the wagon bed. 70

2. In a device of the class described, the combination of a wagon bed with a combined end gate and scoop board, means for adjustably connecting the lower end of the end gate with the lower part of the wagon bed, 75 and means for adjustably connecting the upper end of the end gate with the upper portion of the wagon bed, said means comprising plates extending rearwardly from the wagon bed, said end gate having slots of 80 greater length from top to bottom than the width of said plates from top to bottom, and adapted to receive said plates, said plates being of such length as to permit the end gate to slide rearwardly thereon a limited 85 distance without moving off the plates, and means for limiting the outward sliding movement of the end gate on said plates.

3. In a device of the class described, the combination of a wagon bed, with a combined scoop board and end gate, a cleat below the lower end of the wagon bed and flush with the rear edge thereof, a hinge slidably mounted in said block, means on said hinge for limiting such sliding movement, said 90 hinge having a portion designed to be secured to the rear surface of the end gate, the parts being so arranged that when the end gate is closed, the hinge is locked against sliding movement whereby when 100 the end gate is swung rearwardly at its upper end the hinge may be slid for a limited distance and the lower edge of the end gate and the pivotal line of the hinge will be supported by said cleat. 105

Des Moines, Iowa, February 10, 1917.

SOLOMON PENTICO.
